CLAIM

I claim the ornamental design for a single-serve container with surface ornamentation, as shown and described.

DESCRIPTION

FIG. 1 is a perspective view of a single-serve container with surface ornamentation in its blank, unassembled condition. FIG. 2 is a top view of the single-serve container of FIG. 1. FIG. 3 is a perspective view of the single-serve container of FIG. 1, showing the container in a constructed state. FIG. 4 is a front view of the single-serve container of FIG. 3.

FIG. 5 is a rear view of the single-serve container of FIG. 3. FIG. 6 is a left side view of the single-serve container of FIG. 3.

FIG. 7 is a right side view of the single-serve container of FIG. 3.

FIG. 8 is a top view of the single-serve container of FIG. 3; and,

FIG. 9 is a bottom view of the single-serve container of FIG. 3.

Features shown in broken or dotted lines in the drawings are not part of the claim. Also, any shading presented in the accompanying drawings is provided merely to highlight the contour of the invention and is not intended to be illustrative of texture or gloss.
